UNITED STATES PATENT OFFICE.

ORVILLE WRIGHT AND JOHN H. FARLOW, OF BALTIMORE, MARYLAND.

DRAFT-RIGGING FOR CARS.

SPECIFICATION forming part of Letters Patent No. 739,770, dated September 22, 1903.

Application filed June 15, 1903. Serial No. 161,550. (No model.)

To all whom it may concern:

Be it known that we, I ORVILLE WRIGHT and JOHN H. FARLOW, citizens of the United States, residing at Baltimore city, in the State of Maryland, have invented new and useful Improvements in Draft-Rigging for Cars, of which the following is a specification.

The object of our invention is the production of an improved draft- and buffing gear or rigging for cars which shall be adapted to embrace as a part thereof, according to the service demanded, a single spring or tandem springs for receiving the main strains of towing and buffing, which shall be comparatively simple in construction and comprised of suitable elements so combined and arranged that repairs may be made when necessary very easily and quickly and without taking the car to the shops, which shall be very strong and capable of withstanding the shocks of severe service, which shall distribute the strains throughout the length of the draft-timbers or supports or sills, which shall admit of the removal and replacement of a coupler and draw-bar without the removal of the spring mechanism, and which shall possess other and desirable novel features of construction constituting the same a superior instrumentality for performing the requisite functions.

With this end and purpose in view our invention consists in certain novelties of construction, arrangements, and combinations of elements and parts hereinafter set forth and specified in the claims.

The accompanying drawings illustrate a complete example of the physical embodiment of our invention constructed according to the best mode we have so far devised for the practical application of the principle.

Figure 1 is a longitudinal sectional view in elevation of Fig. 2. Fig. 2 is a half top plan view and a horizontal sectional view of the draft-beams and the parts of the rigging combined therewith as seen when removed from the floor-frame. Fig. 3 is a face view of a draft-beam or support. Fig. 4 is a cross-section of Fig. 3 through one of the lugs and at one side of the other lug. Fig. 5 is a longitudinal section of Fig. 3. Fig. 6 is a face view of a yoke. Fig. 7 is an end view of Fig. 6. Fig. 8 is a longitudinal section of Fig. 6.

Fig. 9 is a cross-section of Fig. 1, one half taken on a line through a follower-block and the other half through the lugs on a draft-beam and on a yoke.

Referring to the several figures, the numeral 1 designates the central stringers of the car-floor frame; 2, the end sill; 3, the buffer-block; 4, the draft sills or beams, which are of metal in this example; 5, bolts which secure the draft-beams to the sills and buffer-block; 6, the top lugs on the draft-beams; 7, the bottom lugs; 8, holes through the lugs for bolts; 9, the front elongated slots in the beams; 10, the center slots; 11, the rear elongated slots; 12, strengthening-ribs around the slots, which also provide large bearing areas for the pins; 13, the carry-iron; 14, the angle-iron friction-plate; 15, the draw-bar yokes; 16, the slots at the front ends of the yokes; 17, the central elongated slots; 18, the end elongated slots; 19, the narrowed portions of the yokes; 20, the lugs on the faces of the yokes; 21, bolts which unite the draft-beams and pass through the lugs on the same; 22, the draw-bar with a coupler-head of any approved type; 23, a slot in the draw-bar; 24, a hole in the end of the draw-bar; 25, the front follower-block; 26, an elongated slot in the block; 27, lugs on the block, the front one being seated in the end of the draw-bar and the other one supporting the end of a spring; 28, the rear follower-block; 29, a slot in the rear follower-block; 30, a lug on the face of the block to support the end of a spring; 31, a follower-pin; 32, the enlarged central portion of the pin located between the lugs on the draft-beams and on the yokes; 33, two perforated follower-plates on the follower-pin; 34, the front spring; 35, the rear spring; 36, the three equalizing-pins, and 37 represents cotters in the ends of the pin.

On reference to the drawings it will be seen that when the parts are assembled the front equalizing-pin closely fits the slot in the draw-bar and the ends are located within the centers of the elongated slots in the draft-beams, that the rear pin is located at the rear ends of the slots in the draft-beams and in the yokes, that the central pin is immovable and that the front follower-block and the yokes move relative to this pin, that the follower-pin moves longitudinally, and that the

lugs on the yokes engage both the follower-plates and move between the lugs on the draft-beams a distance equal to the narrowed portion thereof.

5 The *modus operandi* is as follows: In drawing, the draw-bar imparts motion to the yokes and the front and rear equalizing-pins, the lugs upon the yokes engaging the front follower-plate advances it, compressing the front 10 spring, the rear follower-block simultaneously compresses the rear spring, and when the springs have been compressed, for instance, two inches the lug on the rear follower-block, the rear lug on the front follower-block, and the ends of the follower-pin come in contact. Simultaneously the front and rear pins reach the ends of the slots in the draft-beams and all additional strains above those taken by the springs are imparted 15 to the draft-beams at three points in each, as is obvious.

In buffing the operation is substantially the same. The rear equalizing-pin is stationary. The slots in the yokes allow the yokes to move over the rear and central pins, and the slot in the front follower-block allows the block to move rearwardly with the draw-bar. When the springs have been compressed, the additional strains are transmitted 20 to the draft-beams at three points in each, and as thus distributed no injury will result to any part of the rigging.

The method of assembling the several parts and elements of the gear and the method of 25 replacing an element or part will be readily understood by any person skilled in the art from an inspection of the drawings, and therefore the same need not be specifically set forth.

40 While we have illustrated and described only one complete example of the physical embodiment of our invention, we do not thereby intend to limit the scope thereof to such embodiment, inasmuch as the principle may 45 be applied under different forms and by other modes. Metallic center sills with slots may be used in place of the sills and draft-beams shown, the draft-beams made separate or integral, the shape of the follower-blocks be 50 altered, a single spring used in place of two springs, and other modifications, substitutions, omissions, additions, and changes be introduced at the will and choice of the manufacturer without constituting substantial departures.

55 What we claim as new, and desire to secure by Letters Patent, is—

1. The combination in a draft and buffing gear, of a coupler and draw-bar, a front follower-block; a rear follower-block; a spring or springs between the blocks; slotted yokes; and equalizing-pins a plurality of which are movable within slots of the gear; said yokes being movable relative to two of the pins.

60 2. The combination in a draft and buffing gear, of a coupler and draw-bar, a front follower-block with an elongated slot; a rear

follower-block; a spring or springs between the blocks; slotted yokes; and equalizing-pins; the slot in the front follower-block being adapted to move over one of the pins, and the yokes over two of the pins during the act of buffing.

70 3. The combination in a draft and buffing gear, of a coupler and draw-bar; a front follower-block; a rear movable follower-block; a spring or springs between the blocks; yokes each having two elongated slots; equalizing-pins; and slotted supports for the pins; two of said pins being adapted to move within 80 slots, and one of the elongated slots of the yokes to move over a pin during the act of drawing.

4. The combination in a draft and buffing gear, of a draw-bar and coupler; supports 85 having two elongated slots; two pins movable in the slots; a central equalizing-pin; two slotted yokes the central slots being elongated each side of the pin; a slotted follower-block; a rear follower-block; and a spring or springs 90 between the follower-blocks; said draw-bar being provided with a slot and within which is located a pin.

5. The combination in a draft and buffing gear, of a coupler and draw-bar; a slotted 95 follower-block in the rear of the end of the draw-bar; a rear follower-block; a spring or springs between the blocks; slotted supports or draft-timbers; slotted yokes; and equalizing-pins within the slots of the draw-bar, 100 blocks, yokes, and supports; the front slots in the supports being elongated each side of the front equalizing-pin.

6. The combination in a draft and buffing gear, of a coupler and draw-bar; slotted supports; follower-blocks; slotted yokes; equalizing-pins; tandem springs; follower-plates; and means for supporting the tandem springs; said yokes being provided with lugs upon 105 their inner faces which engage the follower-plates; the equalizing-pins passed through the follower-blocks, yokes, and slotted supports; and the springs being located between the follower-blocks.

7. The combination in a draft and buffing gear, of a coupler and draw-bar; slotted supports; follower-blocks; slotted yokes; equalizing-pins; tandem springs; follower-plates; and a follower-pin; said yokes having lugs to engage the follower-plates; said pins passed 110 through the slotted supports, follower-blocks, and yokes; and each of the springs located between a follower-block and a follower-plate.

8. The combination with a draft and buffing gear, constructed substantially as set 115 forth, of tandem springs; follower-plates; a follower-pin; follower-blocks; equalizing-pins; a coupler and draw-bar; slotted supports; and yokes each having a lug adapted to engage the follower-plates, said equalizing-pins passed through the yokes and follower-blocks and two pins movable within the slotted supports.

9. The combination with a draft and buff-

ing gear, constructed in substance as described, of tandem springs; two follower-plates; yokes with lugs; a fixed abutment; slotted supports; front and rear follower-blocks; and equalizing-pins located within the slotted supports and passed through the follower-blocks and yokes.

10. The combination with a draft and buffing gear, of tandem springs; two follower-plates; an abutment; yokes with lugs; and a follower-pin with an enlarged central portion.

11. The combination with a draft and buffing gear, of draft-beams; an abutment formed by lugs on the draft-beams; two follower-plates; two follower-blocks; two springs; yokes each having a lug; equalizing-pins; and a follower-pin having an enlarged portion located between the upper and lower lugs upon the draft-beams, said equalizing-pins passed through slots in the draft-beams, follower-blocks, and yokes; and said enlarged portion of the follower-pin engaging the follower-plates.

12. The combination in a draft and buffing gear of supports each having three slots; a draw-bar with a slot; a follower-block in the rear of the draw-bar and having an elongated slot; a slotted rear follower-block; a spring between the follower-blocks; slotted yokes located each side of the follower-blocks, two of said slots being elongated; and three equalizing-pins within the slots of the several slotted elements; the central pin being fixed and the end pins being movable within the slots.

13. The combination in a draft and buffing gear, of supports each having three slots; a draw-bar with a slot; a front follower-block in contact with the end of the draw-bar and having an elongated slot; a slotted rear fol-

lower-block; a spring between the follower-blocks; two yokes each having three slots the central and rear ones elongated; and three equalizing-pins within the slots of the several slotted elements; the middle pin being immovable and the end pins movable and the rear pin when the parts are assembled occupying the rear portions of the elongated slots in the supports.

14. The combination in a draft and buffing gear, of slotted supports; slotted follower-blocks located between the supports; a spring between the follower-blocks; two slotted yokes located between the supports and one on each side of the follower-blocks; equalizing-pins; and a coupler and draw-bar; the front pin being located in the center of the slots in the supports and movable with the draw-bar.

15. The combination in a draft and buffing gear of slotted supports, the end slots elongated; a rear follower-block with a slot; slotted yokes between the supports, two of said slots being elongated; a spring in front of the follower-block; a movable pin passed through the rear slots in the support, the follower-block, and the rear slots in the yokes; a fixed pin located within the slots of the supports and the slots of the yokes; and a draw-bar and coupler; the front ends of the yokes being secured to the draw-bar, and said yokes movable relative to the fixed pin.

In testimony whereof we affix our signatures in presence of two witnesses.
